UNITED STATES PATENT OFFICE.

JAMES BOWERS, OF NEWARK, NEW JERSEY.

DESIGN FOR A CORSET.

SPECIFICATION forming part of Design No. 17,048, dated January 4, 1887.

Application filed July 2, 1886. Serial No. 206,920. Term of patent 7 years.

To all whom it may concern:

Be it known that I, JAMES BOWERS, a citizen of the United States, residing at Newark, in the county of Essex and State of New Jersey, 5 have invented and produced a new and original Design for Corsets; and I do hereby declare the following to be a full, clear, and exact description of the invention, such as will enable others skilled in the art to which it app pertains to make and use the same, reference being had to the accompanying drawing, and to letters of reference marked thereon, which form a part of this specification.

The figure of the drawing represents in front 15 elevation a corset embodying the design, which relates more particularly to the bust or breast portions of the same.

In said drawing, A A indicate the usual or ordinary transverse bust-pieces, below which 20 are central pieces, B B, which appear to be interrupted in their upward courses by said transverse bust-pieces and gore-shaped pieces C C, and at the ends of which are the front pieces, D D, and side pieces, E E.

25 The leading feature of the design consists of a corset in which the bust or breast portions, each present to view another transverse piece or panel above the piece or panel A, which extends with said piece or panel A uninterrupted from said side and front pieces, and presents a face which is ornamented with a series of vertical and parallel ribs, stripes, or lines, as shown.

The ornamented section or panel F lies above and parallel with the section A, and terminates 35 at or is hidden from view by the front and side pieces, and said sections A and F are not interrupted in their horizontal courses by the panel B extending vertically therethrough. The panel A is ornamented by horizontal or 40 longitudinal lines, ribs, or stripes, and the panel F by vertical lines, ribs, or stripes, or by lines, ribs, or stripes which lie approximately at right angles to those of the panel A, said vertical lines, ribs, or stripes being in a 45 series on or over the face of the panel.

The upper edge of the corset may be ornamented by lace G, in any ordinary manner.

What I claim is—

The design for a corset herein described, 50 which consists, essentially, of a corset having the upper bust portions, between the sections D E, present to view the sections A C C B F, the sections A and F extending uninterruptedly above the sections C C B from the section D to the section E, and the section F being ornamented over the face thereto with a series of vertical lines, ribs, or stripes, as herein set forth.

In testimony that I claim the foregoing I 55 have hereunto set my hand this 28th day of June, 1886.

JAMES BOWERS.
